UNITED STATES PATENT OFFICE.

SAMUEL HORELICK, OF PITTSBURGH, PENNSYLVANIA, ASSIGNOR TO PITTSBURGH
TRANSFORMER COMPANY, A CORPORATION OF PENNSYLVANIA.

TRANSFORMER-TAP CHANGER.

Application filed February 12, 1923. Serial No. 618,448.

This invention relates to transformers and particularly to transformers immersed in oil in a containing tank. It is sometimes desirable in connection with such transformers 5 to connect into circuit more or less of the winding, primary or secondary, according to the service desired. For this purpose certain points of the winding are carried out by tap connections so that the length of 10 the winding may be varied by connecting the leads to different taps. In an oil cooled transformer the tap terminals are preferably within the tank and are therefore difficult of access and to change the connections 15 it is necessary to open the tank and reach down within it.

The object of this invention is to avoid this necessity of opening the tank to change the tap connections. In the apparatus of 20 this invention the tap terminals are kept within the tank and control means for them is extended out through the cover so that the operator at the outside of the tank may make the shift from one tap to the other 25 without opening the tank.

Further objects of the invention particularly in providing tap changing means which will be simple and durable in form and accurate in operation will appear from 30 the following description taken in connection with the accompanying drawings, in which—

Fig. 1 is a vertical sectional view through the top of a transformer tank showing the tap changing means in elevation,

Fig. 2 is an elevation of the tap changing device with certain of the connected parts shown in section,

Fig. 3 is a plan view of the slab support for the top terminals,

Fig. 4 is a plan view of the control means outside of the tank, and

Fig. 5 is a diagram illustrating the circuits.

In the specific embodiment of the invention shown in the drawings a transformer tank 4 having a top 5 contains a transformer having a core 6 and winding 7. Extending upward from a frame 8 supporting the core are bolts 10 and supported by these bolt 15 is a supporting slab 11 of insulating material such as asbestos ebony for the tap terminals 12, 13 and 14, these tap terminals being connected by conductors 12', 13' and 14' to desired portions of the secondary winding.

The other end of the secondary winding is

conducted by lead 15 to the outside of the tank through a bushing (not shown) while the tap terminals may be connected selectively by the apparatus of this invention to the lead 17 passing through bushing 18 to 60 the outside of the tank. The leads 30 of the primary winding in this specific embodiment of the invention pass out of the tank through high tension bushings not shown.

The secondary lead 17 is connected to the 65 vertical rod 20 fastened within the casting 21 carrying the blade 22 adapted to be inserted between the leaves 23 of terminals 12, 13 or 14. Each of these terminals is rigidly fastened to the slab 11 and passes 70 therethrough as a downwardly extending bolt 24 adapted to be connected to the corresponding lead 12', 13' or 14'. The rod 20 is slidably mounted in a bushing 25 (Fig. 2) 75 passing through the slab 11 so that upon lifting the casting 21 the latter may be turned around the axis of the rod 20 so as to bring the knife 22 in position to fit into either of the terminals 12, 13 or 14 as desired and thus connect the rod 20 and lead 17 80 in circuit with the selected tap of the secondary winding.

To permit the knife switch 22 to be moved from the outside of the tank the rod 20 above the casting 21 is bolted at 26 to an insulating block 27 connected at its upper end 28 to a rod 29 extending up through the tank cover 5 and carrying at its upper end a handle device 31. The tank top 5 is provided with a flanged opening for the rod 29, 90 the flange 32 of this opening having fitted within it a block 33 welded in place as indicated at 34 and recessed at the center to contain the packing material 35 held in place by the stuffing box bushing 36 pressed down by bolting means 37. A number of bolts 38 screwed into the block 33 are extended upward to adjustably support a table piece 39 held rigidly in place on these bolts. Positioned above this support 39 and rigidly 95 fastened to the handle 31 and rod 29 is a cross arm 40 carrying a pin 41 adapted to pass into apertures 42, 43 and 44 of the support 39 beneath, these apertures being so positioned that when the pin 41 registers 100 with either of them the knife switch 22 will register with the corresponding lead terminal 12, 13 or 14 within the tank.

The rod 29 moves vertically through the cover 5 so that by lifting the handle 31 the 110

pin 41 and knife switch 22 are removed from the corresponding recess 42, 43 or 44 and terminal 12, 13 or 14. The handle 31 is then turned to bring the pin 41 into register with one of the other recesses and the knife blade correspondingly moves into position to enter between the leaves 23 of the desired terminal 12, 13 or 14. Then upon depressing the handle 31 the pin 41 enters its recess and the knife switch 22 enters the next contact at the corresponding terminal so as to change the tap connection. A pivoted latch 43' may be provided engaging under the support 39 to normally hold the movable parts in depressed position. In order to change the connection from one tap to the other it will then be necessary to release this latch 43'. Where it is desired to make the device secure against change from one tap to another a bolt 44' between cross arm 40 and support 39 may be used to hold the movable parts against upward movement. The pin 41 is made sufficiently long so that when it is withdrawn from the hole 42, 43 or 44 the knife switch blade will be clear of the leaves 23 of the terminal 12, 13 or 14, and the switch connection is thus made or broken by vertical movement of the blade.

With the tap changer of this invention the shift from one tap to another is controlled entirely from outside of the tank while the actual switch connections are closed or opened within the tank and preferably below the surface of the oil. It is not necessary therefore to open the tank at any time during the changing. The formation of the apparatus in two main parts with the connection which may be of any desired length permits the switch means to be conveniently placed in any desired position in the tank. When the tank cover 5 is to be removed the interior and exterior means may be disconnected by withdrawing bolt 26 or 28 so that the switch means of the tap changer may be left in set position on the slab 11 and the control means in place on the cover. Then upon replacing the cover 5 it is only necessary to reinsert the removed bolt and the tap changer will be again ready for use.

While the invention has been described in connection with a specific embodiment having three tap terminals, it is obvious that any desired number of tap terminals may be provided to be connected and disconnected in the manner shown and the invention is not confined to the details shown but is intended to cover any modifications thereof falling within the scope of the appended claims.

I claim:

1. The combination with a container for electrical apparatus, of a support in fixed position within said container, a relatively movable switch member carried by said sup-

port and engaging tap terminals from said apparatus, a removable cover for said container, a relatively movable actuating means carried by said cover and a detachable connection between said actuating means and said switch member adapted to be disengaged to permit the cover to be removed without disturbing said switch member.

2. The combination with a container for electrical apparatus, of a support in fixed position within said container, a relatively movable switch member carried by said support and engaging tap terminals from said apparatus, a removable cover for said container, a relatively movable actuating means carried by said cover and extending outside thereof, and a detachable connection between said actuating means and said switch member adapted to be disengaged to permit the cover to be removed without disturbing said switch member or said actuating mechanism.

3. In a tap changer for transformers the combination with an interior switching means adapted to be positioned within a transformer tank and having a switch member movable linearly into and out of contact with tap terminals and rotatably to change from one terminal to another, of control means for said switch member adapted to be positioned outside of the transformer tank, and detachable connecting means between said control means and said switch member, said control means comprising a member movable with said switch member and a fixed member adapted to receive and hold said movable member when said switch is in position to make contact with one of said tap terminals.

4. The combination with a tank, a transformer therein, a cover for said tank and a tap changer for said transformer comprising switching means in said tank control means therefor on said cover and a detachable connection between said switching and control means to permit removal of said cover without disturbing the positions of either of said means.

5. The combination with a tank, a transformer therein, a cover for said tank, of a tap changer for said transformer comprising circuit closing means in the tank, operating means therefor on the cover and a detachable connection between said circuit closing and operating means to permit the removal of said cover without disturbing the positions of either of said means and a device engaging said operating means to lock said tap changer in any of its circuit closing positions.

6. A tank adapted to contain electrical apparatus, a sheet metal cover for said tank formed with a stuffing box, a tap changer for said electrical apparatus comprising switching means located within said tank and operating means comprising a rod slid able

125

130

through said stuffing box to move said switching means to open circuit position, a plate mounted on said stuffing box and a latch on said operating means adapted to engage said plate to prevent movement of said rod to circuit opening position.

7. In a tap changer for transformers the combination with an interior switching means adapted to be positioned within a transformer tank and having tap terminals and a switching member movable linearly into and out of contact with said terminals and rotatably to change from one terminal to another, of control means for said switch member adapted to be positioned outside of the tank and comprising a reciprocable, rotatable rod member passing through from the outside to the inside of the tank and connected to said switching means, a handle member mounted on said rod and reciprocable and rotatable therewith to operate said switching means, and means connected to said rod member outside of said tank, and rotatable with said handle to determine the angular positions of the rod corresponding to the engaging positions of said switching member.

SAMUEL HORELICK.
